UNITED STATES PATENT OFFICE

FLETCHER SCHAUM, OF PHILADELPHIA, PENNSYLVANIA, ASSIGNOR TO FLETCHER WORKS, OF PHILADELPHIA, PENNSYLVANIA, A CORPORATION OF PENNSYLVANIA

AUTOMATIC CONTROL MECHANISM

Application filed November 16, 1927. Serial No. 233,996.

This invention relates to an automatic machine control mechanism of the perforated card type and it consists in the novel features and arrangement hereinafter described and claimed.

An object of the invention is to provide a machine control mechanism or device having means for throwing into action, in properly prescribed sequence, the several features of an apparatus or manufacturing machine, that the said features may function in properly timed relation to produce the desired result. The device may be used to advantage in conjunction with Jacquard looms, batch mixing or compounding apparatus and all other machines or apparatus requiring automatic means for throwing their active features into action in accord with a prescribed rhythm and in properly timed sequence.

Still another object of the invention is to provide an automatic control mechanism similar in its broadest aspect to a jacquard mechanism.

In the well known forms of jacquard controls, however, there are a plurality of hooks and needles used and a knife for operating certain of the hooks that had been actuated or selected by the needles.

The present invention contemplates the doing away with the separate knife and with the needles so that the rods which take the place of the ordinary form of hooks are directly actuated by the faces of the card which are mounted on the shaft that moves the cards into position.

In other words a movement of the shaft and its card thereon also directly operates the rods connected with the instrumentalities of the machine to be operated.

With these and other objects in view the machine control mechanism includes in combination with other elements and features a series of perforated cards similar to those used in a standard Jacquard loom. The cards are linked together in the form of an endless belt or chain and the chain is mounted for movement in an orbital path. Means are provided for shifting the chain bodily at regular intervals of time so that the cards

of the chain which is at the active point in the orbit will present the solid area of its face to the ends of certain push rods or bars of a set of such rods or bars whereby they are moved and operate the instrumentalities with which they are connected. At the same time the perforation or perforations of the said card may receive the remaining rod or rods of the series so that they will remain at rest and inactive.

When the cards are assembled in the form of a chain and connected together, they may be arranged to vary the sequence of operation of the rods, to vary the order of operation thereof and to vary the intervals of duration of activity or the periods of inactivity thereof.

In the accompanying drawings:—

Fig. 1 is a top plan view of the automatic machine control mechanism.

Fig. 2 is a side elevational view thereof showing the parts at one position.

Fig. 3 is a view similar to that shown in Figure 2 and showing the parts at another position.

Fig. 4 is a longitudinal sectional view of the automatic machine control cut on the line 4—4 of Fig. 1.

Fig. 5 is a fragmentary plan view of the automatic machine control mechanism and showing the parts at other positions than as shown in Figure 1.

As illustrated in the accompanying drawings the automatic machine control mechanism is mounted upon the supporting base 1. This base may be the frame of a loom, batch mixing apparatus or any other machine or apparatus with which the control mechanism is used.

Standards 2 are mounted upon the base 1 and a shaft 3 is journaled for rotation in the upper ends of the standard and bridges the space between the standards. A pulley wheel 4 is fixed to one end of the shaft 3 and a belt 5 is trained around the pulley wheel 95 and is adapted to rotate the said wheel and shaft. Any other suitable means may be provided for rotating the shaft 3.

Eccentrics 6 are mounted upon the shaft 3 at points between the standards 2 and are 100

spaced from each other. The bases of the standards 2 are provided with slots 7 and bolts 8 pass through the said slots and are screwed into the supporting base 1. By 5 loosening the bolts 8, the standards may be shifted along the supporting base 1 and when the standards are adjusted to desired points upon the base, they are fixed or secured at such points by tightening the 10 bolts 8.

Frame sides 9 are mounted upon the supporting base 1 and are disposed parallel with relation to each other. Cross bars 10 and 11 are connected at their ends with the 15 frame sides 9 and are spaced from each other in parallel relation and bridge the space between the frame sides 9 and support slidable rods which will be shortly described.

The frame sides 9 are provided at their 20 upper portions with recesses 12 upon the lower edges of which are mounted guide strips 13.

A shaft 14 is provided with enlarged cylindrical end portions 15, which ride upon 25 the said guide strips 13. The end extremities of the shaft 14 are journaled in pitmen bars 16 and the said bars are provided with eccentric straps 17 which surround the eccentrics 6. As the shaft 3 rotates, the eccen- 30 trics 6 are carried around the axis thereof and through the straps 17, the pitmen bars 16 are reciprocated and the shaft 14 and the cylindrical portions 15 thereof are caused to slide along the guide strips 13.

The cylindrical portions 15 are provided 35 at their outer ends with angular flanges 18 which move along the side edges of the guide strips 13 and hold the shaft 14 parallel with relation to the shaft 3. The flanges 40 18 are provided with radially projecting rounded corners 19.

Dogs 20 are pivotally mounted at the sides 45 of the frame members 9 and are provided at their upper edges with hooks 21 which are normally held in the path of movement of the rounded corners 19 by flat springs 22 also mounted upon the frame sides 9 and which bears at their free ends against the lower edges of the dogs 20.

When the shaft 14 is moving away from 50 the hooks 21, the cylindrical portions 15 slide upon the guide plates 13 as hereinbefore stated and when the shaft 14 is moving toward the hooks 21 and one of the corners 55 19 comes in contact with the hooks, the peripheral portions 15 of the cylinder are arrested while at the same time the axis of the shaft 14 is moved over and beyond the hooks 21, thus the shaft 14 in its reciprocatory 60 movement is given a turn or partial rotation at the end of the stroke. Rods 23 are pivotally connected at one end with the frame sides 9 and are provided on their under sides with friction plates 24, which 65 rest upon the edges of the uppermost round-

ed corners 19 of the flanges 18 as best shown in Fig. 2 of the drawing. Traction springs 25 are connected at one end with the free ends of the rods 23 and connected at their other ends by means of links 26 with the supporting base 1. Thus the plates 24 are held resiliently in contact with the uppermost corners 19 of the flanges and the shaft 14 is restrained against turning or rotary movement until such time as one of the 70 corners 19 comes in contact with the hooks 21 when the said shaft is partially turned as hereinbefore described.

The intermediate portion of the cylinder shaft 14 is provided with angularly disposed faces 27 best shown in Fig. 4 of the drawing and the said intermediate portion of the said shaft is further provided with openings 28, which pass diametrically through the shaft and which are located along the median dimensions of the faces 27. The shaft 14 is further provided in the vicinity of the ends of the faces thereof without outstanding studs 29.

A yoke member 30 is pivotally mounted upon the base support 1 and a roller 31 is journaled between the upper ends of the arms of said yoke. A spring 32 is connected at one end with the intermediate portion of the yoke and at its other end with the supporting base 1. The spring 32 is under tension and with a tendency to hold the roller 31 spaced away from the shaft 14. A series of cards 33 are connected together by means of links 34 whereby the said series of cards form an endless chain or belt which is trained around the roller 31 and the intermediate portion of the shaft 14. Each of the cards 33 is provided with suitable openings 35 and with stud receiving openings 36, the said openings 36 being adapted to receive certain of the studs 29 as the card is moving around the axis of the shaft 14. The openings 35 which are provided in the cards 33 register with certain of the openings 28 in the shaft 14.

All of the cards are of the same length, breadth and thickness and the length and breadth of each card is substantially the length and breadth of each of the faces 27 of the shaft 14. In that the roller 31 is being held away from the shaft 14 by the spring 32 and inasmuch as the said chain of cards is trained around the roller 31 and the shaft 14, the upper and lower runs of the chain of cards are maintained in proper taut condition.

Rods 37 are mounted for longitudinal sliding movement in the cross bars 10 and 11 and carry stop pins 38 which are located between said cross bars. Coiled springs 39 surround the rods 37 and bear at one end against the cross bar 11 and at their other ends against the pins 38. The springs 39 are under compression with a tendency to 125

hold the inner ends of the rods 37 toward the axis of the shaft 14.

Levers 40 are pivotally mounted upon the supporting base 1, one of them being located in alignment with each of the rods 37. Links 41 connect the aligned rods and levers together. The levers 40 are provided at their outer edges with rows of notches 42 and the said notches are adapted to receive 10 pull elements 43 which are connected with the throwing in mechanisms of the machine (not shown) and to which the control mechanism is applied. As the shaft 14 is reciprocated, the chain of cards is correspondingly moved and when the shaft arrives 15 at the end of its out stroke, it is turned as hereinbefore described, so that a new card is brought to position with one of the faces 27 of the shaft opposite the inner ends of 20 the rods 37. As the shaft 14 moves toward the inner ends of the said rods, the face of the said card will strike the inner ends of certain of the said rods, while the inner ends of the other rods will be received in the registering openings 35 and 28 of the card and shaft 14 respectively. Thus rods which enter the openings will not be moved, but will remain at a state of rest, while those rods which are struck by the surface of the card 25 will be moved longitudinally and, in turn the moving rod or rods through the links 41 will swing those levers 40 with which they are connected, whereby the said levers will move the pull elements 43 connected thereto 30 and thus the instrumentalities of the machine to which the control is applied will be thrown into action or operation.

Each rod 37 is provided with a stop pin 38' adapted to engage the face of the bar 11 40 when the actuated rods 37 are returned to normal position.

It is obvious that by varying the arrangement of the cards in the chain and by varying the arrangement of the openings 35 in the cards, the instrumentalities of the machine to which the device is applied may be thrown into action at the desired intervals and that the extent of the operation or action of said instrumentalities may be varied 50 or controlled so that desired cycle of the several actions may be had to bring about the desired results of the machine that is to be controlled.

The cards may be arranged to vary the 55 sequence of operation of the rods, to vary the order of operation thereof and to vary the intervals of duration of activity or the periods of inactivity thereof.

From the foregoing it will be seen that 60 I have produced an automatic control mechanism wherein a number of parts that are necessary in the ordinary form of jacquard mechanism are dispensed with.

It will also be seen that the movement of 65 the shaft that carries the cards directly ac-

tuates the fingers or rods that are selectively operated by the certain cards.

Thus I have disposed of the ordinary needles that in turn actuate the hooks, which hooks were heretofore in turn operated by the raising and lowering of the knife. 70

It will also be seen that the force exerted by the movement of the cylinder is in a direct line with the plane of the rods, so that there is very little, if any, lost motion 75 in the actuation of the rods.

The control has proven extremely efficient in service, and as will be understood is easy to assemble, relatively cheap to manufacture and is of compact assemblage. 80

It will be understood that many slight variations or changes might be made in the arrangement or in the structure without departing from the spirit and scope of the invention. 85

Having thus described my invention what I claim as new and desire to secure by Letters Patent is:

1. An automatic control comprising a series of perforated cards mounted for movement about an intermittently rotatable reciprocatory cylinder, a series of rods movably mounted for reciprocation in the path of the cards, each rod being connected with a distinct controlling lever means and each card when reciprocated adapted to engage certain of the rods and through the rod so engaged energize the controlling means connected thereto and means for reciprocating the entire series of cards. 90

2. An automatic control comprising a series of rods mounted for movement and pivotally connected with the lever means to be controlled, means for holding the rods at normal position, a chain of cards arranged in prescribed order, means for moving the chain to present the cards successively to the series of rods, each card having surface area adapted to engage certain of the rods and openings adapted to receive the other rods of the series, and means for moving the presented card toward the rods to rod engaging and receiving position, to move the rod being engaged by the surface area of the card and through the rod move the controlling lever means connected thereto and means for reciprocating the entire series of cards. 105

3. An automatic control comprising a series of rods mounted for movement and connected with the upright means to be controlled, individual spring means, means for holding each of the rods at normal position, a chain of cards arranged in prescribed order, means for moving the chain to present the cards successively to the series of rods, said means including a cylinder having its axis disposed in the plane in which the axes of the rods lie, said chain of cards being trained around said cylinder, said cyl- 110

inder having openings passing diametrically therethrough, each card having a surface area adapted to engage certain rods of the series, and means for moving the presented card toward the rods to rod engaging and receiving position, to move the rod being engaged by the surface area of the card and through the rod move the controlling means connected thereto and means for reciprocating the entire series of cards.

10 4. In an automatic control device, spaced frame members, a cylinder shaft mounted thereon, means including a pitman for reciprocating and intermittently turning the cylinder shaft, a series of bars slidably mounted and having their ends disposed opposite and normally spaced from the cylinder shaft, a plurality of levers respectively connected to said bars and a link connection between each respective bar and lever a series of cards linked together in the form of a chain, said chain being trained around the cylinder shaft, a yoke member pivotally mounted between the frame members, a roller journaled upon the yoke member and disposed between opposite runs of the chain of cards, a spring connected at one end with the yoke member and at its other end to a fixed point and serving to hold the chain in taut condition and means for reciprocating the entire series of cards.

15 5. In an automatic control device spaced frame members, cross bars connected at their ends with the frame members and bridging the space between them, said bars being spaced in parallel relation, rods slidably mounted in the bars, springs surrounding the rods and located between the bars, said springs bearing upon one of the bars and connected with the rods and serving to hold the rods at normal position upon the bars, levers adapted to be connected to the devices to be controlled, link means for connecting the rods with lever to be controlled, 20 a cylinder shaft mounted for sliding movement and intermittently rotating movement upon the frame members, means for sliding and rotating the cylinder shaft, studs carried by the shaft, a series of cards linked together and adapted to move around the cylinder shaft, the cards having openings for receiving the studs and other openings adapted to receive certain of the rods.

25 6. An automatic control comprising a series of slidable elements connected with the means to be controlled and a series of predeterminedly arranged actuating elements mounted for movement in an orbital path and movable as an entity whereby said actuating elements are successively presented to the slidable elements, said actuating elements having surface areas adapted to slide certain of the slidable elements while the balance of the slidable elements remain at rest by penetrating the actuating elements,

and means for reciprocating the entire series of actuating elements.

In testimony whereof I affix my signature.
